CARTON FEEDING MECHANISM

Hugh F. Conser, Detroit, Mich., assignor to
 Shedd-Bartush Foods, Inc., Detroit, Mich., a
 corporation of Michigan

Application January 5, 1946, Serial No. 639,193

2 Claims. (Cl. 271—1)

1

The present invention relates to an improved mechanism for feeding flat articles, such as folded cardboard box blanks, from a stack of such articles in a magazine; and the present invention constitutes an improvement over the mechanism for the same purpose incorporated in the Carton folding machine disclosed in applicant's co-pending application, Serial Number 593,639, filed May 14, 1945.

In many types of machines, including those employed in folding, forming, or filling cardboard containers, it is customary to supply the machine with a stack of flat, folded cardboard boxes or box blanks. This stack is usually placed in a suitable magazine and means are provided for feeding the blanks one at a time from the magazine to the portions of the machine which perform subsequent operations thereon. In order to insure successful operation of the machine, the feeding mechanism must operate positively and successfully to feed a box blank on each cycle of operation without missing a blank or injuring any of the blanks in the magazine. Prior mechanisms employed for this purpose, including that disclosed in the above mentioned application, perform this function in a generally satisfactory manner so long as the blanks are fairly flat and uniform in character. However, occasionally during shipment of box blanks they become distorted and hence do not lie either flat or in a uniform manner in the magazine. As a result, the feeding mechanism occasionally misses or destroys a blank, thus interrupting the cycle of operation of the machine.

Accordingly, it is the general object of the present invention to provide an improved form of feeding mechanism which will operate positively without injury to the blanks regardless of whether or not the blanks are perfectly flat or are somewhat distorted when they are placed in the magazine.

Another object of the invention is to provide a mechanism of the above mentioned type which is peculiarly suited for use on the type of flat, folded box blanks in which four sides of the box are permanently joined together at their edges to form a collapsible parallelepiped with end closure flaps secured to the ends of the four side walls. One typical box of this type is disclosed more fully in applicant's above mentioned application.

Another object of the invention is to provide a box blank feeding mechanism of the type mentioned which is also effective to open up or square the blank as it is delivered from the magazine.

2

Other objects and advantages of the invention, which include the provision of a box blank feeding mechanism which is simple and rugged in construction and foolproof in operation, will become apparent from the following specification, the accompanying drawings, and the appended claims.

In the drawings:

Figure 1 is a fragmentary side elevation of that portion of a box blank folding machine incorporating the feeding mechanism of the present invention;

Figure 2 is a plan view of the mechanism shown in Figure 1;

Figure 3 is a longitudinal section taken on the line 3—3 of Figure 2;

Figure 4 is a transverse section taken on the line 4—4 of Figure 3;

Figures 5, 6 and 7 are fragmentary views showing the condition of a box blank during three successive stages in its removal from the magazine.

Referring to the drawings, and particularly Figures 1 and 2, the present invention is shown incorporated in a machine having a frame work generally indicated at 1 which may be of any suitable construction, the particular machine illustrated being a portion of the complete box blank folding machine disclosed in applicant's above mentioned co-pending application. That machine is effective to extract folded box blanks one at a time from a magazine, square them and close the end closure flaps at one end of the box preparatory to filling. Since the present invention relates only to the mechanism for feeding box blanks one at a time from the magazine and squaring them, the remaining portions of the machine are not illustrated. It is understood, however, that they may be of any desired construction and may perform any desired operations upon the squared blank.

The frame work 1 includes a pair of parallel channel irons 2, which support in any desired manner a table or top floor construction including a pair of horizontal plates 3 and 4, which are spaced apart at their inner edges to receive a reciprocable slide, indicated generally at 5. The slide 5 is made up of a top bar 6 and underlying bar 7. The edges of the latter bar project beyond those of the top bar 6 and into recesses defined by a pair of longitudinal angle irons 8 and 9, which are fixed to the under side of the plates 3 and 4, respectively, by means of spacing blocks 10 and 11 to form a guide way for the slide. The machine is provided with a magazine indicated generally at 12 and positioned immediately above

the plates 3 and 4 in the manner best shown in Figures 2, 3 and 4. The magazine is constructed in such a manner as to support a vertical stack of box blanks. It comprises a pair of side walls 13 and 14 which are illustrated as of lattice construction and a pair of side wall plates 15 and 16. Plate 16 completely closes one side wall of the magazine except for a narrow vertical slot 17 which permits passage of the carton blank discharging hook hereinafter described. The plate 15 terminates at a lower edge 18, located a sufficient distance above the plates 3 and 4 to permit passage of a squared or substantially squared box blank.

An elongated strip 19, of sheet metal or the like, extends along the full width of the wall 13 at the lowermost end of the magazine. The strip 19 slopes upwardly at an angle from the plate 4, as best shown in Figure 4, and its upper edge is bent horizontally at 20 to form a horizontal ledge extending the full width of the wall 13 and spaced above the plate 4. The opposite edge of the strip 19 is bent inwardly to form a flange 21 which rests directly upon and may be fastened in any suitable manner to the plate 4. In the region beyond the magazine, to the left as viewed in Figure 3, the strip 19 is bent at the fold lines 22 and 23 to form a vertically extending section 24 which is connected to the inclined section by an intermediate triangular section. The vertical section 24 is preferably made approximately the same height as that of the squared box blank, as best shown in Figure 7, and the upper edge of the section 24 is bent inwardly to form a flange 25 to retain the squared box blank against upward displacement. The right-hand end of the flange 25 is bent upwardly at 26 to insure entry of the squared blanks beneath the flange.

As best shown in Figure 4, the ledge 20 formed within the magazine by the strip 19 engages the under side of one edge of the lowermost box blank in the magazine and thus assists in holding the stack of blanks in elevated position in the magazine. In order to prevent dropping of the opposite edge, the magazine adjacent the shelf 20 is made of less width than the width of the box blank with the result that the blanks extend across the magazine at an acute angle to the walls thereof and bear against the opposite side of the magazine, in the manner shown in Figure 4. The entire magazine may be made of less width than the box blanks, if desired. However, as shown in the drawings, the main body of the magazine is of a width equal to that of the flat box blanks but the lower portion is reduced in width by a plate 27 which has a lower vertically extending portion 28 which extends to approximately the height of the shelf 20 and an outwardly sloping upper section 29, the upper edge of which merges with the side wall 14 of the magazine. While only one box blank is illustrated in Figure 4, it will be understood that a plurality of additional blanks will be stacked above the blank there illustrated.

Each blank comprises four side walls 30, 31, 32 and 33 permanently joined at their edges to each other. The ends of the side walls are provided with any suitable form of end closure flaps. For purposes of the present invention, however, it is only necessary to mention the end closure flap 34, which is formed on side wall 30. In order to permit use of the box blanks in the mechanism of the present invention, the flap 34 must have a portion which is exposed when the blank is

viewed from the under side of the stack. This may be achieved by providing a flap on the wall 32 which is shorter than the flap 34 or by cutting away one corner of the flap on the side wall 32 adjacent the juncture of that side wall with the side wall 33.

The mechanism for engaging and discharging the box blanks from the magazine comprises a generally hooked-shaped member 35 having a long tapered point 36, the extremity of which is bent slightly upward at 37. The point 36, as best shown in Figures 3, 4, 5, 6 and 7 is in the form of a flat vertical sheet provided with a horizontal flange 38 at its lower edge, which flange likewise tapers in width toward the point. A feed dog 39 is fixed to the under side of horizontal flange 38 adjacent the rear end of the point 36.

The main body of the hook 35 comprises a relatively large flat sheet 40, the major portion of which lies below plate 4; and the latter plate is provided with a slot 41 through which the hook projects. A pair of stub shafts 42 and 43 are fixed to the plate 40 and serve as journals for a pair of spool type rollers 44 and 45 which fit within slots 46 and 47 respectively, formed in a vertical plate 48. The plate 48 is fixed in any desired manner in spaced relation to the adjacent channel iron 2, as best shown in Figure 4. As a result of this construction, the slotted plate 48 and the rollers 44 and 45 support the hook 35 in the position shown in the drawings and guide it for movement in a path determined by the form of the slots 46 and 47. The slot 41 may also assist in holding the hook in a vertical plane.

Means are provided for reciprocating the hook between the solid line position shown in Figure 3 and the dotted line position shown in the same figure. This means comprises a link 49 which is pivoted at one end on an extension of the shaft 43 and at the other end to the upper end of a lever 50. The lever 50 is pivoted at 51 to a stationary portion of the machine and carries a roller 52 indicated in dotted lines in Figure 1, which fits within a groove 53 formed in the face of an eccentric disk 54. The disk 54 is fixed to a shaft 55 which is rotated by means of a belt 56 from any suitable source of power, not shown. Rotation of the disk 54 oscillates the lever 50 about the pivot 51 and thus effects reciprocation of the hook 35 between the limit positions illustrated in Figure 3.

In order to permit removal of the hook 35 from the machine for repair or replacement, the slots 46 and 47 are extended rearwardly beyond the rearward limit positions of the spools 44 and 45, and are provided with enlarged extremities 57 and 58 through which the spools may be withdrawn by lateral movement. In order to permit such movement, the rear end of the slot 41 is widened at 59, as best shown in Figure 2. It will be understood that such removal of the hook 35 may be effected only after it is disconnected from the lever 50 or link 49.

The shape of the slots 46 and 47 is such that on forward movement of the hook from the position shown in solid lines of Figure 3, the hook travels in a horizontal path until its point has entered approximately half way into the box blank. Such entry of the hook into the box blank between the walls 30 and 32 is insured by reason of the fact that in the fully retracted position, the hook has cleared the lower side wall 32 and any tab which may be carried on the end of that wall and has engaged and slightly lifted the flap 34 on the wall 30. The slight upward

deflection 37 of the point of the hook provides further assurance that the point will enter between the walls 30 and 32. After the hook has entered approximately half way into the carbon, the hook will on further advancing movement begin to lower bodily with respect to the plates 3 and 4 due to the downward deflection of the slots 46 and 47. By the time the hook has projected fully into the box blank and just before the dog 39 on the hook engages the rear edge of the side wall 32 of the box blank or a flap on wall 32, the hook will have completed its downward movement and the horizontal flange 38 of the hook will lie in a plane spaced above the top surface of the plates 3 and 4 by an amount slightly in excess of the thickness of the box blank material, thus holding the side wall 32 of the blank against the plates 3 and 4.

As best shown in Figures 5, 6 and 7, entry of the hook into the carton blanks spreads the walls 30 and 32 of the blank apart, thus partially squaring the blank, as best shown in Figure 5. This squaring of the blank decreases the distance between that edge of the blank which is common to side walls 30 and 33 and that edge which is common to the side walls 31 and 32. This reduction of the distance between these two edges permits the latter edge to slide progressively down the surface of plate 27 until it occupies a position at the same elevation, or lower, than ledge 20. The parts are so arranged that the downward movement of the hook is correlated with the rate at which the blank may be lowered as a result of the squaring operation. The final lowering movement further squares the carton blank and removes it from the ledge 20. It will be noted that in the position illustrated in Figure 6, the wall 33 of the blank is bearing against the strip 19. This is the position which the parts occupy immediately before engagement of the carton blank by the dog 39.

Thereafter, as the hook continues to advance, it ejects the carton blank beneath the lower edge 18 of the magazine wall 15. As the blank moves away from its position beneath the magazine, the wall 33 of the blank rides along the strip 19. Consequently, it is elevated from the position shown in Figure 6 to the fully squared position shown in Figure 7. The position of the parts illustrated in Figure 7 corresponds to the extreme advance position of the hook 35, which position is indicated by dotted lines in Figure 3. It will be noted that during the movement of the carton from the position shown in Figure 6 to the position shown in Figure 7, the horizontal flange 38 of the hook holds the bottom wall 32 of the blank against the top surface of plates 3 and 4.

Immediately upon completion of the forward movement, the hook 35 is retracted by the eccentric disk 54 and the connecting lever 50 and link 49 leaving the fully squared carton blank in position along side of the vertical section 24 of the strip 19. During such initial retraction, the hook passes freely beneath the lowermost carton blank in the magazine, which blank is then occupying the position illustrated in Figure 4. The final return movement raises the hook beneath the blank and carries the point of the hook beyond the bottom wall 32 and into engagement with the flap 34, in the manner indicated in Figure 3, in which position it is ready to begin the next advance movement.

The lever 50, which effects reciprocation of the hook 35, also simultaneously reciprocates the

slide 5 by reason of a link 60 which connects the lever 50 with a bracket 61 fixed to the under side of the bar 7. The slide carries a feed dog 62 which engages the previously ejected and squared carton blank at the same time that the dog 39 on hook 35 engages a carton blank within the magazine. Consequently, as the slide 5 and the hook 35 move forward together, the previously ejected and squared carton blank is advanced by the dog 62 ahead of the blank which is being advanced by the hook. The dog 62 may advance the squared cartons to any suitable instrumentality, such as the end closure mechanism disclosed in said co-pending application. During such advance, the carbon is guided by the previously mentioned vertical section 24 of the strip 19 which engages one side of the squared carton, and an upstanding wall 63 mounted on the plate 3, which engages the opposite side wall of the carton.

It will be observed that the mechanism is effective to eject a carton from the magazine and fully square it in a single movement. Since the point of the hook is located well above the normal plane of the lower wall 32 of the blank when the hook is fully retracted, it must pass above that wall on subsequent advance regardless of irregularities in the form of the lower wall. Since, in its fully retracted position, the hook engages and elevates a flap on the top wall 30 of the blank, it must be guided beneath the top wall on subsequent advance. Thus entry of the hook into the lowermost blank is positively insured and it is unnecessary to rely upon accurate positioning of the opening in the blank in the path of movement of the point of the hook. While this feature of the invention is peculiarly suited to the ejection of box blanks of the type illustrated, it is applicable to any flat blank having one folded edge to provide a double thickness between which the point of the hook may enter.

Another important feature resides in the fact that the cartons are moved downwardly out of contact with the remaining cartons in the stack before they are advanced, with the result that there is no danger that the hook will injure the remaining cartons in the stack when it ejects a carton or makes its return movement. An important factor in this connection is the support of the stack of blanks in elevated position by engagement of two opposite edges and the withdrawal of the lowermost blank by a distortion or change in its form.

The above described features are not limited in their application to cartons of the type illustrated and may be employed when no subsequent squaring operation is required. However, a further feature of the invention resides in the fact that the carton feeding means, when applied to the illustrated type of blanks, also squares the carton blanks simultaneously with their ejection. Moreover, the initial squaring movement effects release of the lowermost blank from the magazine by reducing the overall width of the blank.

The particular form of mechanism illustrated and described performs a major portion of the box squaring function during the downward movement of the box blank from the stack in the magazine, and completes the squaring operation during subsequent advance movement of the partially squared blank. It will be appreciated, however, that the sloping plate 19 may be positioned vertically with the result that the

complete squaring operation will occur during the downward movement, if desired.

While only one form of the invention is illustrated and described herein, it will be apparent that variations in the details of construction and arrangement of the parts may be indulged in without departing from the spirit of the invention or the scope of the appended claims.

What is claimed is:

1. In a mechanism for feeding flat folded box blanks of the type in which four sides of the box are joined to each other to form a collapsible parallelepiped, a magazine for holding a stack of said flat folded blanks, means defining a ledge engageable with the exposed face adjacent one edge of the blank at one end of said stack to limit endwise movement of said stack of blanks, the wall of said magazine opposite said ledge being spaced from the wall adjacent said ledge by slightly less than the width of the flat blank whereby said end blank extends across said magazine in contact with said walls at an acute angle to said walls such that the flat blanks cannot pass said ledge, a reciprocating pointed blade having progressively increasing dimensions in a direction at right angles to the plane of the folded blanks, means for reciprocating said blade to cause it to enter the endmost blank in the stack and thereby open the blank and reduce its width so that it will pass said ledge, and means for holding the opened blank against the wall opposite said ledge.

2. In a mechanism for feeding flat folded box blanks of the type in which four sides of the box are joined to each other to form a collapsible

10

15

20

30
35

parallelepiped, a magazine for holding a vertical stack of said flat folded blanks, said magazine having a restricted portion adjacent its lower end through which the flat folded blanks cannot pass, and blank discharging mechanism including a blade of progressively increasing dimensions at right angles to the plane of the folded blanks, and means to reciprocate said blade to enter one end of the blank at the lower end of said stack and open the blank sufficiently to permit it to pass said restriction and move the blank downwardly past said restriction, said means being effective thereafter by a continuation of said entering movement to move said blade and blank horizontally in a direction parallel to the joining edges of said four sides of the box blank for feeding said blanks to an associated conveyor mechanism, and stationary means engageable with the blank for completing the opening thereof during said last mentioned movement.
